UNITED STATES PATENT OFFICE.

LEO MILLER CHAPMAN AND JAMES MADISON GELATT, OF LOUISVILLE,
KENTUCKY.

LINOTYPE-MACHINE.

SPECIFICATION forming part of Letters Patent No. 624,454, dated May 9, 1899.

Application filed January 6, 1899. Serial No. 701,343. (No model.)

To all whom it may concern:

Be it known that we, LEO MILLER CHAPMAN and JAMES MADISON GELATT, citizens of the United States, residing at Louisville, in the county of Jefferson and State of Kentucky, have invented certain new and useful Improvements in Linotype-Machines, of which the following is a full and complete specification, such as will enable those skilled in the art to which it appertains to make and use the same.

This invention relates to linotype-machines, and is an improvement on the usual vise-jaw-adjusting devices ordinarily employed in such machines to determine the "measure" of the type to be composed and in making "cut-offs." The machine of this class now in use and to which our improvement relates is shown in the patent to Mergenthaler, No. 557,000. In this machine as ordinarily constructed, in practice, when it is desired to "change the measure" or determine the number of "ems" which shall govern the setting up of the type it is necessary to employ a screw-driver and remove a set-screw and also to adjust and operate a wrench on the screw-shaft which bears the adjusting-nut. In our improvement we do away with the set-screw and the use of a wrench. Another method employed to this end is the placing of type-blanks between the adjusting-nut and the jaw, which often causes trouble and delay. This method we also dispense with.

Our improvement is fully disclosed in the following specification, of which the accompanying drawings form a part, in which like numerals of reference refer to like parts in the several views, and in which—

Figure 1 is a side sectional elevation of a portion of a linotype-machine, showing the vise used in determining the measure of the type and the means employed to change the measure, part of the machine being shown in full lines and the screw-shaft being shown in dotted lines; Fig. 2, an end elevation showing the adjusting devices. Fig. 3 is a transverse section of the block, flange, and details of construction employed in changing the measure and is taken on the line 3 3 of Fig.

2, looking in the direction of the arrows. Fig. 4 is an end view of the flange-piece shown in Fig. 3, and Fig. 5 is a side view thereof.

Referring more particularly to Fig. 1 of the drawings, 7 is a base-block mounted in the front portion of the linotype-machine and adjacent to the type-metal pot. This base-block is constructed in the usual manner, the details of construction being therefore not shown and described, and is chambered to receive the vise-jaws 8 and 11, which are adjustable longitudinally thereof and one of which, 11, is slidably mounted thereon and the position of which determines the measure of the line of type to be set up between them, as usual.

A bracket 13 (seen in Figs. 1 and 2) is secured to the base-block 9 by means of screws or bolts 14, (best seen in Fig. 2,) said screws passing through a plate or block 15, integral with said bracket 13. A screw-shaft 10 is journaled at one end in the bracket 13, as at 17 in Fig. 1, and the other end is supported by a correspondingly-threaded adjusting-nut 12 within the base-block 7, and the screw-shaft 10 and nut 12 are mounted in the base-block 7 within a chamber communicating with the chamber in which are mounted the vise-jaws 8 and 11. The nut 12 projects upwardly and engages the outer end of the vise-jaw 11, as shown in Fig. 1. The screw-shaft 10 is smooth between the bracket 13 and the end of the base-block 7, and the end thereof is squared, as at 18 in Fig. 2. A block 19 is bored and revolubly mounted upon the screw-shaft 10 between the bracket 13 and the end of the base-block 7, the plate 15 being cut away to receive it.

The screw-shaft 10 bears a flange-piece 20, having a collar 21 integral therewith, and the flange 20 is bored to fit the screw-shaft 10 between the bracket 13 and the base-block 7, and the collar 21 also fits said screw-shaft 10 and is keyed thereto, as at 22 in Fig. 1.

The flange-piece 20 is provided with the usual number of perforations 23, circularly arranged therein and bored smooth, whereas in the ordinary machine the perforations 23 are threaded. The block 19 is provided with a deeply-countersunk perforation 24,

(shown in Fig. 3,) the ordinary machine being provided with a block which is only slightly countersunk in the corresponding perforation 24 to receive the head of a set-screw. A pin 25 is inserted in the perforation 24, and the head 26 thereof rests in said countersunk portion, the shank thereof extending normally through the block 19 and into the perforation 23.

10 A supplemental catch - pin 27 is screw-threaded at one end and screwed into the head 26 of the pin 25, which head is bored and threaded correspondingly. The catch-pin 27 is bent at right angles outside of the bore 24 and flattened at the outer end 28, which end may, if desired, be milled.

15 A coil-spring 29 surrounds the catch-pin 27, within the perforation 24, and bears at one end against the head 26 of the pin 25. A plate 30 is secured upon the face of the block 19, adjacent to the outer end of the catch-pin 27, and is perforated to fit the bore of the collar 21 and the pin 34 and also squarely perforated to allow of the exit of the catch-pin 25, which is formed square in cross-section to fit said perforation and cannot turn so as to be unscrewed from the head 26. Against the plate 30 bears the outer end of the coil-spring 29, and it is evident that to withdraw the pin 25 from one of the holes 23 it is only necessary to grasp the catch-pin 27 by the head 28 thereof and pull it outward, drawing with it the pin 25 longitudinally of the perforation 24 in the block 19.

20 30 The square end 18 of the screw-shaft 10 (shown in Fig. 3) is usually turned by means of a wrench when revolving the screw-shaft 10 to adjust the adjusting-nut 12; but I provide it with a crank or handle 31, which is keyed or pinned thereto, and it is evident that when the pin 25 is withdrawn from the perforation 23 in the flange-piece 20 said flange-piece and said screw-shaft 10 may be revolved independently of the block 19.

25 40 An arm 32 is pivotally connected with the block 19, as at 33, by an enlarged end thereof, a pin 34 passing therethrough and through the perforations 35 in the block 19 and communicating with a recess 36 thereof, in which 45 said end 33 of said arm 32 is fitted. A pin 37 passes through the pin 34 to hold it in place. The arm 32 is pivoted to a rod 38, as at 39, and the arm 38 is so operatively connected with the machine as to be intermittently depressed to depress the arm 32 and rotate the block 19, the flange-piece 20, and the screw-shaft 10 to adjust the adjusting-nut 12, and these revolutions described of the screw-shaft 10 by means of the arm 32 occur at predetermined intervals, and a coil-spring 40, secured to the plate 15 at one end, as at 41, and to the arm 32 at the other end, as at 42, raises the arm 32 and the arm 38 and reversely revolves the block 19, the flange-piece 20, and the screw-shaft 10 and reversely adjusts the adjusting-nut 12. The purpose of the above-described 55 intermittent adjustments of the nut 12 is to

press the vise-jaw 11 firmly against the type-blanks between it and the vise-jaw 8 during molding of the type for the press from the molten metal in the type-metal pot, as is fully understood by those skilled in the art of linotyping, and is no part whatever of our invention.

60 The operation of our device will be readily understood from the foregoing description when taken in connection with the accompanying drawings and the following statement thereof.

Having predetermined the desired position 65 on the screw-shaft 10 of the vise-jaw 11, and consequently of the adjusting-nut 12, the head 28 of the catch-pin 27 is grasped and the pin 25 is withdrawn from whichever of the perforations 23 in the flange-piece 20 into which it 70 may project. This movement unlocks the flange-piece 20 from the block 19, which is secured to the arm 32. The screw-shaft 10 being keyed to the collar 21 of the flange-piece 20, said flange-piece and shaft are free to revolve independent of the block 19. The crank 31 is then revolved, revolving the screw-shaft 10 requisite 75 to advance or withdraw the adjusting-nut 12 to such an extent or for as many ems as desired. The perforations 23 in the flange-piece 20 are arranged circularly at such intervals as shall allow of one of the same registering with the perforation 24 when the shaft 10 is revolved to the desired extent. The pin 25 is then allowed to enter the perforation 23 80 registering with the perforation 24, being pressed therein by the spring 29. When the adjusting-nut 12 is in the proper adjusted position on the screw-shaft 10, the vise-jaw 11 is moved slidably into contact therewith, and the mechanism operates as usual, employing the customary function of the vise-jaws 8 85 and 11. The changes which it is necessary to make 90 in the linotype-machine as now constructed to embrace our improvements are four in number: The perforations 23 in the flange-piece 20 must be smooth. The perforation 24 in the block 19 must be countersunk through nearly the entire thickness of the block 19. 95 The bracket 13 or the end of the base-block 7 must be filed to make room between them for the plate 30, secured to the block 19. The square end 18 of the screw-shaft 10 must be provided with a pin or key for the crank 31. 100 It is evident that with the above-enumerated slight changes in linotype-machines they may be so improved with regard to the vise-jaw-adjusting devices thereof as to render the adjustment of said vise-jaw extremely simple 105 and convenient. The catch-pin 27 replaces a set-screw liable to displacement by vibration and requiring considerable waste of time to manipulate, and the crank 31 takes the place of a wrench, liable to misplacement.

Having fully described our invention, we claim as new and desire to secure by Letters Patent—

In a linotype-machine, a vise for holding

the type-blanks while molding the type, said vise being provided with a screw-shaft and a slidably-adjustable member mounted above said screw-shaft, an adjusting-nut mounted upon said screw-shaft and adapted to adjust said slidably-adjustable member, a plate rigidly secured to said screw-shaft and provided with a plurality of circularly-arranged transverse smooth-bored perforations, a block revolvably mounted on said screw-shaft adjacent to said plate and provided with a smooth-bored perforation adapted to register with said perforations in said plate, a pin slidably mounted in said perforation in said block and provided with a bored head, a catch-pin connected with said head and projecting from said perforation in said block, and provided with

an angular portion and head, said block being provided on the outer surface thereof with a plate provided with a perforation through which said catch-pin passes, and a coil-spring mounted in said perforation in said block and bearing against said pin and said outer plate, substantially as shown and described.

In testimony that we claim the foregoing as our invention we have signed our names, in presence of the subscribing witnesses, this 27th day of December, 1898.

LEO MILLER CHAPMAN.
JAMES MADISON GELATT.
